UNITED STATES PATENT OFFICE.

LEE ROY SMART, OF CHICAGO, ILLINOIS, ASSIGNOR TO JOHNSON-WILLIAMSON LABORATORIES, INC., OF CHICAGO, ILLINOIS, A CORPORATION OF ILLINOIS.

DESIGN FOR A RADIO LOOP AERIAL.

Application filed October 2, 1926. Serial No. 19,234. Term of patent 3½ years.

To all whom it may concern:

Be it known that I, LEE ROY SMART, a citizen of the United States, residing at Chicago, in the county of Cook and State of Illinois, have invented a new, original, and ornamental Design for Radio Loop Aerials, of which the following is a specification, reference being had to the accompanying drawing, forming part thereof.

Figure 1 is a front view of the radio loop aerial showing my new design.

Figure 2 is a top view of Figure 1, and Figure 3 is an end view of Figure 1.

I claim:

The ornamental design for a radio loop aerial, as shown.

L. R. SMART.
